UNITED STATES PATENT OFFICE.

HENRY EDMUNDS, JR., OF NEW YORK, N. Y., ASSIGNOR TO THOMAS J. MONTGOMERY, OF BOSTON, MASSACHUSETTS.

CONTACT FOR ELECTRIC LAMPS.

SPECIFICATION forming part of Letters Patent No. 288,218, dated November 13, 1883.

Application filed April 5, 1883. (No model.)

To all whom it may concern:

Be it known that I, HENRY EDMUNDS, Jr., of the city and State of New York, have invented an Improvement in Contacts for Electric Lamps, of which the following is a specification.

This improvement is especially available in connecting electric lamps to brackets, chandeliers, or other fixtures, and is intended to insure perfect metallic contact and to allow for connecting or disconnecting the lamp with rapidity.

In the drawings, Figure 1 is an elevation of the lamp complete. Fig. 2 is a vertical section of the socket containing the contacts. Fig. 3 is an inverted plan of the spring-contacts, and Fig. 4 is a plan of the contact-studs.

The electric lamp A is provided with a glass globe, an incandescent-carbon filament, and with conductors passing through the glass, and the same is supported above the base B by a spring, C; and there are hooks d at the ends of the conductors to which the wires of the lamp are hooked; but these devices have before been made, and are not my invention. I also remark that any suitable incandescent lamp may be employed with my improvements next described.

The base B is of insulating material, and it is received into the upper end of the metallic cup F, that is screwed upon the tubular support G, that forms part of the bracket, chandelier, or other support; and usually there will be a switch at H for turning the current on or off; but this switch does not form part of my present invention.

Within the cup F there is a block, S, of insulating material screwed firmly to the end of G. The insulated electric conductors k pass through the tube G and are clamped to the

contact-plates l l' by the screws i, the naked wire being twisted around under the screw-heads.

Upon the respective plates l l' there are contact-studs o o', and upon the under side of the base B there are the spring-contacts n n', shown in Figs. 2 and 3. Each spring has a hole through it for the wire of the spring-hook d to pass through and be twisted around beneath the screw-head t, so as to be secured firmly at the same time as the spring is fastened to the base B. Each spring is bent away from the base, so that its free end can yield, and the parts are placed so that when the base B is inserted into the cup F and the studs r of the base entered into the bayonet-lock slots of the cup, the springs n n' will come over the contact-studs o o'; and as the base B is partially revolved to turn the studs r into the horizontal portions of the bayonet-lock, the springs n n' come into contact firmly with the studs o o' with a rubbing motion that prevents any particles of foreign matter remaining between the metallic surfaces, hence insuring perfect metallic contact.

I claim as my invention—

The combination, with the incandescent electric lamp A, of the base B, the cup F, contact-plates l l', and studs, the insulating-block S, to which the plates l l' are screwed, and the contact-springs n n' upon the inner side of the base B, to which the spring-conductors are attached, and the bayonet-locks for connecting the cup and base, substantially as set forth.

Signed by me this 29th day of March, A. D. 7 1883.

HENRY EDMUNDS, JR.
